UNITED STATES PATENT OFFICE.

WALTER B. TEMPLETON, OF CHICAGO, ILLINOIS.

EXPANSION STUD.

1,413,998.

Specification of Letters Patent. Patented Apr. 25, 1922.

Application filed November 3, 1920. Serial No. 421,476.

To all whom it may concern:

Be it known that I, WALTER B. TEMPLETON, a citizen of the United States, residing at Chicago, in the county of Cook and State 5 of Illinois, have invented certain new and useful Improvements in Expansion Studs, of which the following is a specification.

This invention relates to improvements in what are commonly known as expansion 10 studs, bolts, rivets and like devices which are made hollow and are secured permanently in place to unite two members through which they are passed by having a cast or forged head or flange at one end and by having the 15 metal at the other end extruded and expanded by a swaging tool driven into or through the device. Expansion rivets of this general type are sometimes used for strongly and permanently uniting two or 20 more plates or strips through which they are passed. On the other hand, where two members are united in such a manner that one may have a free swinging or pivotal movement on the other, the pivot stud in 25 such cases has usually taken the form of an ordinary machine screw or a bolt and nut, either of which easily works itself loose and falls out of place. Pivot studs of this screw and bolt type have long been used in lifting 30 jacks and like tools; and the unreliability of such devices has suggested to me the desirability of a pivot stud of simple and cheap construction that will be permanently and immovably held and secured in working 35 position, as a result of which I have devised the pivot stud forming the subject matter of the present invention which adapts the broad principle of the expansion rivet to a special field wherein it has peculiar utility 40 as a pivot stud that will allow perfect freedom of pivotal or swinging movement of one member on another, and yet can never work loose or out of place.

My invention, its mode of use, and the advantages inherent therein will be readily understood and appreciated by persons skilled in the art from the following detailed description, taken in connection with the accompanying drawing in which I have illustrated one simple and practical embodiment of the invention, and wherein:—

Fig. 1 is a front elevation showing a stationary wall or plate and a movable arm or lever permanently pivoted thereon through 55 the agency of my improved expansion stud;

Fig. 2 is a section taken on the line 2—2 of Fig. 1;

Figs. 3, 4, and 5 are perspective detail views, similar to Fig. 2, illustrating the manner of applying and permanently securing the pivot stud in place, and the preferred instrumentalities for performing such operations; and

Fig. 6 is a perspective elevation of the expansion stud in its original form and before 65 it has been partly transformed through application to the parts which it serves to connect.

Referring to the drawings, 5 may designate a flat stationary plate, strip or wall, 70 and 6 an arm or lever which is to be pivotally mounted upon the member 5. As one practical example of an application of this invention which I have found to be of great utility in practice, the wall 5 may represent 75 an internal fixed wall of the frame of a lifting jack, and the pivoted member 6 may represent a pivoted pawl-reversing trigger. The stationary member 5 is formed with a circular aperture 7, and the pivoted 80 member 6 is also formed with a slightly larger circular aperture 8.

In the apertures 7 and 8 is fitted my improved expansion stud which consists of a short tubular member of malleable metal 85 having a general cup-shape. This member has a round body portion 9 which fits the hole 7 of the wall 5, it has an inner annular shoulder 10 which fits against one side of the wall 5; it has an outer annular shoulder 90 11 which fits against the corresponding side of the pivoted member 6, and between the shoulders 11 and 10 it has a round bearing 12 for the pivoted member 6 and fitting the hole 8 of the latter. 95

The bore 13 of the expansion stud is of uniform diameter, for the most part, and at its inner end communicates freely with a conical opening 14 formed in and through a transverse end wall 15 of the stud. 100

To apply the stud, the latter is first positioned as shown in Fig. 3, the stud being entered through the holes 7 and 8 of the two members 5 and 6 which are to be connected. A tapered swaging tool A is then entered 105 into the bore 13, and is driven clear through the apertured bottom wall 15 by hammer blows upon a driver B. Figs. 3, 4 and 5 clearly and simply illustrate the manner in which the swaging tool A is driven through 110

the expansion stud by the driver B; this having the effect of extruding and radially spreading the comparatively soft metal forming the bottom wall 15 of the stud out 5 around that portion of the rear surface of the wall 5 which immediately surrounds the opening 7 of the latter. By this operation the expansion stud is strongly and permanently secured to the wall 5, and the movable member 6 is pivotally supported on its bearing 12 and confined against escape by the shoulder 11 on one side and the proximate wall of the member 5 on the other. The inner annular shoulder 10 prevents the possibility of the pivoted member 6 becoming unduly clamped or jammed against the member 5 so that it will not swing freely.

It will be observed that the swaging tool A tapers in opposite directions from a maximum diameter a which is slightly greater than the uniform diameter of the driver or follower B. This swaging tool is used in all situations where the tool A can be recovered after it has been driven through the stud, for the reason that it makes the return movement of the driver B very easy. Of course, the two tools A and B may be combined into a single tool having a tapered forward end, but such a tool usually requires some force for its removal after it has been driven through the stud far enough to extrude and expand the metal at the closed end of the latter.

While I have shown and described the expansion stud as forming a pivot stud for two relatively movable members to be permanently united, yet it may also be used to advantage as a hollow expansion rivet to permanently unite two members which are not relatively movable, as for instance, a combined rivet and vent for a tubular washing barrel, or as a steam distributor, and hence I do not limit the invention in its broadest aspects to its use as a pivot stud.

It is believed that the structural features, uses and advantages of this simple device will be readily apparent from the foregoing description. Manifestly the exact form and proportions may be varied to accommodate different uses and situations without involving any departure from the principle or sacrificing any of the advantages of the invention. Hence, I reserve all such variations and modifications as fall within the spirit and purview of the appended claims.

I claim:

1. An expansion stud adapted to permanently and pivotally attach a movable member to a stationary member, consisting of a

hollow member of malleable metal having 60 a pair of spaced annular shoulders adapted to bear against the surfaces of said stationary and movable members respectively, and at one end thereof an apertured transverse wall adapted to be expanded, by a swaging 65 tool driven therethrough, against the opposite surface of said stationary member.

2. An expansion stud adapted to permanently attach a pivotal member to and on a stationary member, consisting of a generally cup-shaped member of malleable metal having adjacent to one end thereof inner and outer annular shoulders adapted to bear against the surfaces of said stationary and pivotal members respectively, and 70 at the opposite end thereof a centrally apertured transverse wall adapted to be expanded, by a swaging tool driven therethrough, against the opposite surface of said stationary member.

3. An expansion stud for permanently mounting a pivotal member on a stationary member, comprising a tubular member of malleable metal having adjacent to one end thereof an annular shoulder adapted to bear 85 against the surface of said pivotal member, a narrower annular shoulder adapted to bear against one surface of said stationary member, and a bearing for said pivotal member between said shoulders; said tubular 90 member having at its other end a transverse wall formed with a central conical aperture adapted to receive the pointed end of a swaging tool whereby said transverse wall may be radially expanded against the opposite surface of said stationary member.

4. The combination with a pair of members having registering apertures, of an expansion rivet adapted to permanently unite said members and consisting of a hollow 100 member of malleable metal having a body portion fitting the apertures of said members, annular shoulders at one end bearing against corresponding walls of said members, and an apertured transverse wall at its 105 other end expanded against a side of one of said members.

5. The combination with a pair of members having registering holes of different diameters, of an expansion rivet for permanently uniting said members and consisting of a tubular member having body portions fitting the apertures of said members respectively, annular shoulders bearing against corresponding walls of said members, and a 110 transverse wall expanded against a side of one of said members.

WALTER B. TEMPLETON.
